UNITED STATES PATENT OFFICE.

KAJA P. TOGSTAD, OF MADDOCK, NORTH DAKOTA.

SAFETY-PARACHUTE FOR AVIATORS.

1,227,344.

Specification of Letters Patent. Patented May 22, 1917.

Application filed February 21, 1917. Serial No. 150,105.

To all whom it may concern:

Be it known that I, KAJA P. TOGSTAD, a citizen of the United States, residing at Maddock, in the county of Benson and State of North Dakota, have invented new and useful Improvements in Safety-Parachutes for Aviators, of which the following is a specification.

This invention relates to a safety parachute for aviators, the object of the invention being to provide a device of this character which may be worn upon the person of the aviator, and which will normally be in a collapsed or inoperative position, but is adapted to open and spread automatically in the event of the aviator falling or jumping from the machine, to check the speed of descent and bring the aviator to a safe landing.

20 A further object of the invention is to provide a device of this character which is simple of construction, reliable and efficient in action, and which will be at all times ready for use when the aviator occupies his seat upon the machine.

With these and other objects in view, the invention consists of the features of construction, combination and arrangement of parts hereinafter fully described and 30 claimed, reference being had to the accompanying drawings in which:—

Figure 1 is a sectional side view showing the device as normally worn by the aviator when not occupying his seat in the machine.

Fig. 2 is a similar view showing the device as arranged and worn by the aviator when seated.

Fig. 3 is a similar view showing the device in use for a supporting action.

Fig. 4 is a vertical longitudinal section through the staff sections and belt with parts in the position shown in Figs. 1 and 2.

Fig. 5 is a view similar to Fig. 4 of the same parts in the position shown in Fig. 3.

Fig. 6 is a detail view showing the lashing.

In carrying my invention into practice, I provide a belt 1 adapted to surround the 50 body of the aviator and to be secured in position by suitable straps and buckles 2. This belt serves as a support and attaching means for the parachute, which comprises a collapsible parachute body 3 carried by 55 a pair of divided staff sections 4 and 5. The

body 3 is mounted directly upon the staff section 4 and is preferably of the ordinary umbrella type, being provided with suitable ribs and stretchers forming a frame having a fabric covering, and which is 60 adapted to open and close in the same manner as an ordinary umbrella.

The two staff sections 4 and 5 are hingedly or pivotally united, as shown at 6, for folding and unfolding actions, as herein-after described, and the shaft section 4 is provided at its pivoted end with an arm or projection 7 pivotally coupled to the upper end of a sliding bar or rod 8 movable longitudinally within and through the staff 70 section 5.

The staff section 5 is hollow and is designed to normally stand in a substantially vertical position with its lower end disposed in proximity to the upper rear portion of the belt 1, and the rod 8 is provided with a latch 9 to engage a keeper eye or loop 10 on said belt, whereby the staff member 5 may be supported in such position.

The lower end of the rod or bar 8 terminates in an eye 11 which engages an eye 12 upon the belt 1 at a point below the keeper member 10, whereby the staff section 5 is swiveled to the belt, to adapt the belt, under certain conditions, to have free swing 85 motion thereon.

Mounted upon the rod or bar 8 within the hollow staff section 5 is a sliding head or abutment member 13, and inclosed within said hollow staff section and encompassing 90 the rod or bar between said abutment member 13 and a stationary abutment member 14 in the hollow staff section is a coiled spring 16, which is fixedly connected with the abutments 13 and 14 and is adapted to 95 exert its contractile energy to draw the rod or bar 8 downward within the staff section 5 and thus through a pulling action upon the arm 7, to swing the staff section 4 and parachute body to an upright position.

By reference to Figs. 1 and 2 it will be seen that when the parachute is folded the staff 4 and parachute body are swung downwardly and rearwardly at an angle to a position behind the staff section 5, which is normally maintained in an upright position against pivotal movements on the swivel connections 11 and 12 by engagement of the latch 9 with the keeper 10. When the staff section 4 is swung downwardly to a folded 110

position the arm 7 draws the rod or bar 8 upwardly to move and retain the latch 9 in engagement with the keeper 10 against the resistance of the spring 16, which is thereby 5 expanded and put under tension, so that as long as the staff 4 remains in a folded position the staff 5 will be supported in an upright position and against pivotal motion.

For the purpose of normally holding the 10 staff and parachute body in folded position, as when the aviator is not occupying his seat, a lashing 17 is provided, which may consist of strings fastened to the tip of the rod section 4 with their free ends arranged to 15 be passed about and tied around the belt 1, whereby the parachute body will be held down against the action of the spring. The aviator may thus, while engaged in various duties before or after a flight, wear the device 20 without liability of the parachute being thrown into action, the lashing holding the parachute body against upward movement.

When, however, the lashing is removed, 25 and the parachute body and staff 4 are free for swinging movement, it will be evident that the spring 16 will be free to contract, thus swinging the staff section 4 to an upright position in alignment with the staff 30 section 5, and simultaneously depressing the rod or bar 8 so as to release the latch 9 from engagement with the keeper 10. The parachute will then be free to fill and spread and the staff section 5 to have universal motion upon the belt, so that in the event that 35 the aviator should fall or jump out of the machine he will be suspended in a horizontal position from the staff sections and the parachute body will open and arrest the speed of 40 descent and bring the aviator to a safe landing. The operation of the device in this connection is clearly illustrated in Fig. 3.

In the use of the device the aviator applies it to his person in the manner shown and 45 the swinging staff section is held down by means of the lashing, allowing the aviator to walk about while the parachute is maintained in a supported and collapsed position. After the aviator assumes his position in the 50 seat 18 he releases the lashing 17 so that the staff 4 will be free for operation but will be brought to bear against the seat back 19 whereby it will be held from action unless the aviator moves out of the seat. Thus if 55 the aviator should fall or be thrown out of his seat or should jump from the machine the parachute will be immediately thrown

into action in an obvious manner to insure a safe descent.

From the foregoing description, taken in 6 connection with the drawings, the construction and mode of use of my improved safety 65 parachute will be readily understood, and it will be seen that the device of this character is provided which may be worn without discomfort and which when set for action will always be in readiness for immediate use.

I claim:—

1. A safety parachute attachment for 70 aviators comprising a belt adapted to be secured to the person of the aviator, a staff section swiveled to the belt, a second staff section pivotally connected with the first-named staff section, a parachute body carried by the second staff section, means for normally connecting the first-named staff section with the belt to hold said staff section in an erect position, and means for simultaneously releasing said holding means 75 and throwing the pivoted staff section and 80 parachute body into position for action.

2. A safety parachute attachment for aviators comprising a belt adapted to be secured to the person of the aviator, a staff 85 section swiveled to the belt, a second staff section pivoted to the first-named staff section, a parachute body carried by the second-named staff section, an actuating rod connected with the pivoted staff section, a 90 latch device carried by the rod to engage the belt, and a spring upon the rod for releasing the latch and swinging the second-named staff section and parachute to an operative position. 95

3. A safety parachute attachment for aviators comprising a belt adapted to be worn by the aviator, a keeper member upon said belt, a lower staff section, an upper staff section pivotally mounted upon the lower staff 100 section, a parachute body carried thereby, a rod slidably mounted in the lower staff section and pivotally connected to the upper staff section, a pivotal connection between said rod and the belt, a latch carried by the 105 rod to engage the keeper on the belt to hold the lower staff member in an upright position, and a spring acting upon the rod for moving the same to release said latch member and swing the upper staff member and 110 parachute body to an upright operative position.

In testimony whereof I affix my signature.
KAJA P. TOGSTAD.
